UNITED STATES PATENT OFFICE.

LAFOREST A. SHATTUCK, OF BLOOMSBURG, PENNSYLVANIA.

FOUNTAIN-PEN.

SPECIFICATION forming part of Letters Patent No. 443,628, dated December 30, 1890.

Application filed September 26, 1889. Serial No. 325,170. (No model.)

To all whom it may concern:

Be it known that I, LAFOREST A. SHATTUCK, a citizen of the United States, residing at Bloomsburg, in the county of Columbia and 5 State of Pennsylvania, have invented certain new and useful Improvements in Fountain-Pens; and I do hereby declare the following to be a full, clear, and exact description of the invention, such as will enable others 10 skilled in the art to which it appertains to make and use the same.

My invention relates to a fountain-pen which is organized with an annular ink-weir or suspension-passage open to the air in the forward end of the nozzle, wherein ink is allowed to accumulate, and by means chiefly of adhesive attraction this ink-choked passage furnishes support for the main column of ink in the reservoir; and it consists, first, in an 15 improved combination wherein a longitudinally-adjustable ink and air governing device in the form of an ink attraction or suspension rod is adjusted within the case or holder, with its anterior reduced portion suspended intermediate of the walls of the air-exposed passage of the nozzle, forming forward of the heel of the pen an annular suspension-passage or ink-weir and having its forward end projecting loosely through the air-exposed 20 end of said passage, forming an annular air-egress passage, said combination furnishing a novel means for supporting the main column of ink within the fount, and also preventing the precipitation of ink, as is liable 25 to occur in pens having an open air-vent without the presence of this governing device; second, in an improved ink-conduit whereby by means of an eccentrically-disposed ink- 30 passage through it a deeper space may be obtained for the adjustment of the feed-bar and for an air-space or repulsion-chamber above the pen and feed-bar at the front of the nozzle; third, in the combination of said conduit with said governing device frictionally ad- 35 justed therein, so as to subdivide the ink- 40 passage at the upper end of the nozzle, whereby a circulatory system is established, which obviates the necessity and expense of extending the feed-bar into the reservoir, and, fur- 45 thermore, by the forward free end of the 50 governor nearly closing the open end of the conduit beneath the pen an increased amount

of adhesive-attraction surface is furnished, whereby I secure a more even ink-sustaining force and admit only sufficient air for perfect 55 automatic action; fourth, in an improved nozzle whereby greater ease in unscrewing it from the reservoir is obtained, a finger-stop secured for preventing the fingers sliding forward onto the pen, and means provided for a 60 chamber above the feed-bar lip; fifth, in an improvement to the reservoir, whereby a filling-conductor is provided; sixth, in an improved pen-cap, whereby greater ease in removing the same from the case is secured, as 65 well as other advantages hereinafter more fully set forth; seventh, in an improved arrangement of ink-passages, whereby I secure a circulatory system by means of two or more distinct passages communicating rearwardly 70 with the feed-supply at the rear of the nozzle, but all converging forward into one common annular passage or chamber immediately in rear of the heel of the pen, which furnishes a safeguard against the backward pressure of 75 air, forcing the ink out of feeding power to the pen, and, eighth, in other novel features, as will appear in the specification.

Referring to the drawings, Figure 1 is a central vertical longitudinal section of my invention in one form of its embodiment. Fig. 2 is another way of applying the principle employed in Fig. 1. Fig. 3 is another way of employing the same principle in the construction of the nozzle. Figs. 4 and 5 are transverse 80 sections taken, respectively, at the lines *vv* and *ww* of Fig. 1. Figs. 6 and 7 are similar sections of Fig. 2, taken, respectively, at the lines *xx* and *yy*. Figs. 8 and 9 are similar sections of Fig. 3, taken, respectively, at the lines *zz* and *z'z'*. Fig. 9* is a section similar to Fig. 9, except that the passage in the conduit is concentric instead of eccentric. Fig. 10 is a perspective view of the ink and air governor in Fig. 1, and Fig. 11 is a rear end view of the 95 said governor. Fig. 12 is a perspective view of the form of governor shown in Fig. 2. Fig. 13 is a perspective view of a governor and filling-conductor formed in one piece, as shown in Fig. 3. Fig. 14 is a perspective view of the ink-conduit. Fig. 15 is a perspective view of the feed-bar. Fig. 16 is another perspective view of the conduit slightly changed, as in Fig. 2. Fig. 17 is a perspective view of

the conduit and feed-bar formed in one piece, as shown in Fig. 3. Fig. 18 is a central horizontal longitudinal section of the pen-shielding cap, showing one manner of forming it 5 with index-bar and pencil-holder. Fig. 19 is a perspective view of the device shown in Fig. 18. Fig. 20 is a similar section to Fig. 18, showing the device represented in Figs. 18 and 19 slightly changed. Fig. 21 is a detail view of the index cross-bar shown in Figs. 18, 19, and 22. Fig. 22 is a view of the cap with the pencil-socket end left off and the cross-bar secured by a fixed nut which takes its place. Fig. 23 is a cross-section in the 15 line $x' x'$ of Fig. 18, and Fig. 24 is a cross-section in the line $y' y'$ of Fig. 22.

I deem the construction of fountain-pens wherein atmospheric pressure is employed as the chief support of the ink as extremely unreliable, as in such pens the main column of 20 ink is directly exposed to the atmosphere by having an open and unobstructed passage at the mouth of the nozzle beneath the pen. The objection to this is the uneven support 25 of unaided air-pressure, which frequently permits precipitation of the ink through the air-passage when suddenly inverting the pen to write, and when first filled, and when the fount is nearly empty. There is also great 30 liability to "bleeding" from the pen—so much so that such pens cannot be used with safety upon a set of books.

In my various patents on fountain-pens, numbered 390,039, 402,864, and 403,225, I made 35 use of a different principle of ink-support than that now adopted in this application. I heretofore employed a stopper having an independent air-passage, whereby air is introduced into the ink-chamber at a point in rear 40 of the heel of the pen. In my present case the air may be admitted through the ink-passage at its air-exposed end, and by the aid of a combined ink and air governing device in the form of an ink attraction or suspension 45 rod passed through the main ink-passage of the nozzle and suspended within and intermediate of the walls thereof to a point forward of or flush with its open mouth I change the main support of the ink from "air-pressure," so called, to adhesive attraction, as will 50 be more fully described.

Referring to the drawings, A is the reservoir-section of the case or holder, of ordinary construction, except that it has a filling-conductor in the form of a slender rod A', secured in the closed end and centrally arranged within the ink-chamber. This rod is not essential to the working of the pen, except when employed as a direct support to the governor 55 hereinafter described; but it is found useful when filling the reservoir, as the ink will adhere to and travel down this rod, and the spattering of ink from the backward flow of the air is thereby prevented.

B is the nozzle-section of the case, having at its rear end a screw-threaded portion adapted to register with a corresponding

thread in the open end of the reservoir-section, as shown. The forward end of this nozzle is novel in so far that I provide a raised 70 band, abrupt re-enforcement, ridge, or molding a on its periphery for a finger-stop to prevent the fingers sliding forward upon the feed-bar and pen, as they are liable to do without some such protection. This finger-guard 75 molding is preferably formed integral with the nozzle, but may be in the form of a metal ring adjusted to the nose of the nozzle. At the forward end of the seat a^4 of the cap on the nozzle and separated from said cap-seat by a 80 groove a^8 I provide an auxiliary frictional molding a' to insure greater hold for the fingers when unscrewing the nozzle. Within the nose of the nozzle I preferably form a right-angle shoulder by a counterbore at b , Figs. 3 85 and 8, to an extent nearly corresponding to the thickness of the re-enforcement a , in order to secure a deeper repulsion-chamber a^2 above the pen and the feed-bar in the nose of the nozzle, which enables me to make use of 90 capillary repulsion in holding the ink back and keeping the front end of the nozzle clean. The bore of the nozzle in rear of the conduit may be of the same diameter as that of the conduit, or be made smaller, if desired. 95

The conduit B' (shown in Figs. 1, 2, 3, 14, 16, and 17) is in cylindrical form and designed to fit closely within the forward end of the nozzle. It has normally one common passage through it, which is divided at its front end, 100 when the pen C² is in place, into the passages $b' b'$, that b^2 being for the egress of ink and that b' for the passage of an adjustable governing-rod, the suspension of ink, and the egress of air. The passage, which is thus divided forward of the heel of the pen, is preferably eccentrically disposed on the lower side of the axis of the fountain-pen proper, so as to enable me to adjust the pen more properly in line with the central axis of the holder 105 and to give me a deeper air-space at a^2 between the feed-bar lip at its rear end and wall of the nozzle at its front end, and thus preventing ink working up upon the upper lip of the nozzle. Across the forward end of the 110 conduit above the passage b' I cut a transverse pen seat or slot c , conforming to the shape of the pen and deep enough to form a proper support for the pen when forming a feed-bar integral with the conduit, as shown 115 in Figs. 3 and 17; or the pen may be seated as in the manner shown in Figs. 1, 2, 14, and 16 when forming the feed-bar separable. The upper lip d in Figs. 1 and 14 are cut down quite thin, leaving a shoulder e , against which 120 the feed-bar abuts.

C is the feed-bar. It has a thick base curvilinear in form and adapted to fit the space above the lip d and abut against the shoulder e . At a point even with the under lip d' I 125 cut the feed-bar down, forming a shoulder e' and leaving a thin tapering point or lip extending along back of the pen to near its point. The shoulder e' , being adjusted in-

ward beyond the shoulder b , leaves an angular chamber a^2 above the feed-bar lip between its rear end and upper wall of the nozzle, by which means capillary repulsion will keep 5 any accumulation of ink at this point from working over the point of the nozzle. It is found in practice that an angular air-chamber at the mouth of the nozzle holds any accidental accumulation of ink at this point 10 back better than if constructed bell-shaped, as in some known constructions. The under or pen surface of this bar is provided with a suitable ink-channel longitudinally cut to a point immediately in the rear of the slit in 15 the pen; but from this point to its terminus it is made to rest flat on the pen-nib, so as to hold the ink. This feed-bar groove or channel forms with the pen an inclosed continuation of the conduit, so that ink may readily 20 gravitate to the nibs of the pen. I consider this an advantage over a continuous groove or a continuous flat surface, as the ink, being imprisoned immediately in the rear of the pen's nibs, will not work through the pen-slit 25 to the bottom of the pen in quantities sufficient to drop. This method of confining a quantity of ink so near the nibs insures prompt response to a heavy or light downward stroke with the pen.

30 D is the combined ink and air governor. At its upper end it may be made angular and of sufficient size to fit snugly within the upper end of the main ink-passage and is held in position by the angular points impinging 35 against the walls of the passage in such manner as to divide said ink-passage at or near the rear end of the nozzle into two or more distinct passages, as c^2 , for ink and air, said passages, however, converging into one annular chamber, as b^3 , near the heel of the pen, by reason of the governor being made 40 from this point forward to conform in cross-section to but of less diameter than the ink and air passage, through which it passes.

45 From its shoulders or frictional retaining-points e^2 forward to its point it is made slightly tapering longitudinally and preferably round or elliptical in cross-section, so that where it passes through the air-exposed 50 end of the ink-sustaining passage b' beneath the pen, which I term an "ink-weir," it will be suspended loosely therein and separated from the walls of said passage by a thin annular space around it, which space, as the air 55 is forced out, will be filled with a thin film of ink when the pen is inverted to write, and by reason of the attraction existing between the ink and the walls of the passage b' and the surfaces of the governor suspended therein 60 at this point is sufficient to sustain the downward pressure of the main column of ink, and thereby prevent sudden precipitation of the ink through the air-exposed passage, as would be liable to occur without this governor D.

65 Furthermore, as the air can only enter in very small bubbles to compensate for the expenditure of ink in writing, no bleeding can take

place in the pen-point, there being sufficient attraction between the ink and the pen and feed-bar to support what ink passes over the 70 pen. The lower end of the governor is preferably made to project slightly beyond the air-exposed end of the passage in which it is adjusted, or at least be fully flush with it, as by this construction I secure a greater 75 degree of capillary repulsion as an aid to adhesive attraction in overcoming gravity, and thereby more successfully carry out the principle of my invention; but while having regard to this special construction and arrangement provision is made for adjusting the governor longitudinally, so as to give a greater or less feeding power by increasing or decreasing the ink-passage and by controlling the air-entrance to adapt the pen to the different 80 grades of ink used and styles of penmanship.

In Figs. 1, 5, 10, and 11 I have shown the governor having four grooved sides at its upper end, which when the governor is adjusted 85 in the nozzle serve with the nozzle to form four small triangular longitudinal passages for ink and air to pass through, these passages converging forward into one common 90 passage or chamber b^3 at or near the heel of the pen. It is not essential to have more than two distinct passages c^2 , and consequently but two sides, top and bottom, of the governor might be grooved, and the top side in such 95 case is preferably grooved as far forward as the heel of the pen in order to furnish a continuous communication with the passage b^2 to and over the pen. I sometimes extend this top groove clear to the forward point of the governor, and thereby furnish an increased 100 retaining-surface for ink, and, furthermore, radial grooves might be cut in the lower end of the governor.

In Figs. 2, 7, and 12 I have shown the governor attached to a short cylindrical tube or 105 button D', having four grooves, and this cylindrical tube by impingement against the walls of the nozzle holds the governor in place. The governor might be formed like a flat watch-key without any grooves, as its broad portion 110 would impinge against the side walls of the ink-passage, leaving a passage above and below to create a circulation.

In Fig. 3 I have shown the governor D and the filling-conductor A' constructed in one 115 piece, as A^2 , held by a grooved button D^2 , having its frictional hold at the upper end of the ink-chamber in the reservoir and grooved 120 on its periphery for the flow of ink back and forth through it, and thereby provide for longitudinal adjustment; or the device A' might be secured in the same manner as the filling-conductor shown in Fig. 1 is secured. In this 125 case I form an additional passage through the rear end of the nozzle to create a circulation 130 by grooving either the tube D' or the rear end of the conduit at some suitable point on their outer periphery, said groove extending forward to a point at or near the heel of the pen

and there communicating with the main passage of the conduit, as shown. When forming the filling-conductor A' and governor in one piece, having its frictional hold within 5 the reservoir and its free end projecting beneath the pen, I make the passage through the tube D' slightly larger than the governor end of the rod in order to provide for the easy removal of the tube along with the nozzle, as 10 shown in Fig. 3. It is evident that the governor may be formed integral with the tube D', in form similar to the conduit and feed-bar shown in Fig. 3, and grooved on its periphery. In this case the conductor need not 15 extend so far forward as in Fig. 3.

It is immaterial how the governor is constructed in detail so long as it is longitudinally adjustable and its free end adjusted intermediate of the walls of the ink-passage 20 forming an annular ink-weir, as b', forward of the heel of the pen. I find it much better to have two or more distinct passages, as e³ e³, in the manner I have described, in the rear end of the nozzle, and said passages 25 to converge forward into one main passage or chamber b³, as thereby I establish a circulation, which obviates the necessity for and expense of an ink-conducting extension into the feed-supply. It also furnishes a safe- 30 guard against the air which has entered through the ink-passage forcing the ink too far back, as said air will readily escape to the reservoir through one passage, while the ink passes down through another.

It will be seen that my feed-bar C does not extend to or into the feed-supply, (see Figs. 1, 2, and 3,) as I do not require capillary attraction to draw the ink down. For greater convenience I sometimes form the feed-bar 40 integral with the upper lip of the conduit, as shown at C' in Figs. 3, 8, and 17. In many fountain-pens the ink is conveyed to the pen partly by capillary attraction; but in my herein-described device direct passage to the nibs 45 of the pen is provided, and the ink is precipitated to the pen-point by gravity and prevented from dropping at the front of the nozzle mainly by that cohesive power existing between solids and liquids known as "adhesive 50 attraction."

In Figs. 18, 19, 20, and 24 I have shown the pen-cap E formed with a longitudinal air-groove m in the inner periphery, and in Fig. 23 two such grooves are shown, said groove 55 or grooves extending from the open end of the cap a suitable distance inward, so that almost immediately on starting to remove the cap E from the nozzle air shall be able to enter the cap, and thereby prevent the suction 60 of ink from the nozzle while the cap is being removed. This groove also lessens the difficulty of removing the cap from the upper end of the reservoir by admitting air as soon as it is started, and thereby destroying the 65 vacuum and enabling it to be withdrawn with ease. On the closed end of this cap a flat-sided extension G, terminated in a round

screw-threaded end G', is provided, and on this extension a flat cross-bar H, having a rectangular hole through it, is slipped and 70 confined by means of a nut H', said nut being either solid, as shown in Fig. 22, or formed with a cylindrical socketed portion H², adapted to serve as a lead-pencil holder, as shown in Figs. 18, 19, 20, and 23.

The cross-bar H serves as an index and guard, and, being of greater length than the diameter of the cap, forms finger projections whereby to pull the cap from off the nozzle or upper end of the reservoir, said projection 80 also preventing the pen from rolling when resting on a desk, and also serving as an index for insuring the placing of the pen right side up in the pocket.

The cross-bar H might be made integral 85 with the nut, as shown in Fig. 20, in which case the screw-fastening stem G² of the combined cross-bar and pencil-holder will enter into the threaded socket in the closed end portion of the cap, as shown in said figure. 90

It is a great convenience to have a pencil-holder attached to the cap of a fountain-pen, as both pen and pencil are united in a single writing implement. In order to avoid weakening the nozzle end of the pen-cap by cutting the air-vent groove m, I use a material slightly thicker than that usually employed, or if two or more grooves are made use of, as in Fig. 23, they may be made so shallow as not to interfere with the strength of the cap. 95 I sometimes re-enforce the cap, as at a⁶, Fig. 22, from its open end as far back as the grooves are cut, and this re-enforced portion I preferably form octagonal, as more plainly shown in Fig. 24.

The operation of the pen is exceedingly simple. When inverted for writing, the ink in the reservoir is precipitated forward by gravity, its too rapid descent being checked in part by its adhesion to the filling-conductor within the reservoir and the governor within the nozzle. The ink within the nozzle passes around the governor through the channels e³ into the annular chamber b³, and thence over the pen through the ink-channel b² along the 115 pen-surface to the point of the feed-bar, where further progress is prevented by adhesive attraction. Sufficient ink also passes down around the governor to fill the ink-weir or thin annular passage b' beneath the pen to 120 furnish by means of adhesive attraction at that point, aided by capillary repulsion at its open mouth, sufficient support to sustain the main column of ink and prevent its precipitation through the air-exposed end of said 125 ink-weir when air enters to compensate for the expenditure of ink. The governor also controls the ingress of air, which in pens constructed on the principle of air-pressure support for the ink is liable to enter in too large 130 quantities. The importance of leaving the ink-weir beneath the pen open by an annular mouth for air-exit should not be overlooked, as by this means when inverting the pen to

write ink will force the air in the nozzle through the passage readily, thus enabling the ink to reach the pen-point promptly. I find that when a ready means for air-escape is not provided ink will either be held out of feeding power to the pen or be forced out around the pen and into the pen-cap and upon the nozzle. In my device I overcome all difficulties of this character by means of the air-exposed end of the ink-weir; but the primary object of leaving the passage b' open is to provide for the forward and backward movement through it of the tapering point of the governor, and as the mouth of said passage is of less diameter than the main ink-passage the external mouth of the ink-weir may be closed and the flow of ink decreased whenever a slow-feeding pen is desired. In my patents on fountain-pens, numbered 390,039 and 402,864, I regulated the flow of ink to the extent of producing two pens in one by means of an independent air-vent and by the feed-bars made adjustable for a double or single feed; but in my present device I regulate the supply of ink by a governing-rod formed independent of the feed-bar, by which arrangement I produce a writing implement which does the work of several pens with a single feed-bar and without a special air-vent. As my ink and air governor, whether having its frictional hold within the nozzle or reservoir, is applicable to under-feed pens as well as to those having a bar passed through the writing-pen, I do not confine my application of said governor to the special arrangement of feed-bar herein shown. Furthermore, as my improved nozzle having two or more distinct passages at its rear end all converging into one passage immediately in rear of the heel of the pen, whereby a circulatory system is established, is applicable to other constructions of pens, I do not wish to confine myself to the special construction herein described. As my principle of a governor passed through the ink-passage is applicable to pens organized with an air-exposed passage above the pen instead of beneath, I do not confine its application to the special arrangement shown. It is also evident that my governing device when formed separable from the reservoir conducting-rod may be extended rearward, so as to project from the rear end of the nozzle if found desirable to so construct it, providing its forward end is kept flush with or projecting through the front end of the conduit.

I contemplate applying my ink-suspension rod or governor as an attachment to fountain-pens constructed with an open and unprotected passage in the nozzle end, as it effectually overcomes one of the worst objections to such pens.

In my pen my governor is not a feed-bar, but in effect a longitudinally-adjustable valve independent of the pen-seat or pen, it always providing an annular passage between itself and the pen and walls of the ink-passage, and, not being a feed-bar, the pen works independ-

ently of it, whereas in known constructions the pen will not feed without the aid of a rod or "stick" or other analogous device operating in conjunction with it. My pen does not work by manual force upon an elastic nozzle, but feeds by gravity, and the governor is employed to suspend the ink and prevent its discharge from an open nozzle. My governor also controls the flow of ink by regulating the admission of air, while in other constructions no such purpose is fulfilled.

In my pen the tapering annular passage b' suspends the ink and graduates the feed, longitudinal adjustment being provided for, and thus my pen operates on a different plan from the pens heretofore devised.

I claim—

1. A fountain-pen comprising in its construction a filling-conductor, a conduit B' , having an air and ink passage, and a governing device having grooves or channels in communication with said air and ink passage, substantially as described. 85

2. The combination of a feed-bar, a conduit, as B' , having an air and ink passage, a governor independent of the feed-bar dividing said passage into two or more independent passages in rear of the heel of the pen, a nozzle, and an ink-reservoir, substantially as described. 90

3. A fountain-pen comprising in its construction a shouldered feed-bar bearing upon the nibs of the pen, a shouldered conduit, and a channeled governor device suspended in the ink and air passage of the nozzle, substantially as described. 100

4. A fountain-pen provided with a channeled feed-bar bearing upon the nibs of the pen, forming an inclosed ink-channel whereby the ink is fed by gravity, and a non-elastic nozzle having two or more distinct passages at its rear end, said passages converging forward into one annular passage near the heel of the pen, whereby a circulatory system is established within said nozzle, substantially as described. 105

5. In a fountain-pen, in combination, a reservoir, a nozzle, a feed-bar, a writing-pen, and an ink-suspension rod or ink-governor secured within the case at its upper end and having its forward end suspended intermediate of the walls of the passage beneath the pen, so as to form an annular ink-suspension passage 120 or ink-weir open to the air, substantially as described. 115

6. In a fountain-pen, substantially as herein described, wherein the ink is mainly sustained by adhesive attraction within an annular ink-weir open to the air, as b' , a feed-bar in contact with the pen. 125

7. A fountain-pen having a cap provided with an air-groove in rear of its open end and extending to said open end, substantially as 130 described.

8. A fountain-pen provided with a pencil-holding socket H^3 , substantially as described.

9. In a fountain-pen, substantially as herein

described, wherein the ink is precipitated to the pen-point mainly by gravity, the combination, with a reservoir, a nozzle, a pen, a channeled feed-bar bearing upon the nibs of the pen, and a passage open to the atmosphere, of an adjustable ink-suspension rod or governor independent of the ink-feeding bar and extending a suitable distance into the feed-supply and having an anterior tapering point suspended intermediate of the walls of the nozzle to form forward of the heel of the pen an annular ink-weir for the suspension of ink and for regulating the feed by the longitudinal adjustment of said governor, all as set forth.

10. A fountain-pen provided with a non-elastic nozzle, an ordinary split-nib writing-pen, a feed-bar, and an ink and air governing device having frictional retaining-points, as e^2 , and channels, as e^3 , substantially as described.

11. A fountain-pen comprising in its construction a feed-bar, a non-elastic conduit, and a tapered governing device extended through the conduit, or nearly through the same, and held at its rear end by frictional contact-points, as e^2 , and having ink-channels e^3 through its frictional holding device, and having its forward portion of less diameter than the ink-passage of the conduit, so as to form an annular ink-weir, as b' , substantially as described.

12. A fountain-pen provided with a channeled feed-bar and a governing-rod independent of said feed-bar secured at its upper end within the ink-chamber, with its forward free end loosely projecting through the ink-passage of the nozzle to a point forward of the heel of the pen, so as to form an annular adhesion-passage or ink-weir, as b' , substantially as described.

13. In a fountain-pen having a plurality of passages at the rear end of the nozzle and an inclosed ink-channel along the pen, the annular passage forward of the heel of the pen, whereby by means of adhesive attraction between the ink and the walls of said passage and the surface of the governing-rod suspended intermediate thereof the main column of the ink is sustained and the ingress of air controlled, substantially as described.

14. A fountain-pen comprising in its construction a feed-bar bearing upon the nibs of the pen and a governor detached from the feed-bar and extending from the ink-supply a suitable distance into the nozzle end of the case, said governor by its peculiar construction forming with the said end of the case an ink-weir, as b' , beneath the pen and open to the atmosphere, substantially as described.

15. In a reservoir writing implement comprising in its construction a split-nib pen, a feed-bar, a non-collapsible nozzle, and an ink-suspension rod or governor passed through the air-exposed passage of the nozzle, forming forward of the heel of the pen an annular passage and having its forward end adapted

to increase or decrease said passage by longitudinal adjustment, substantially as described.

16. As an attachment to a fountain-pen provided with a feed-bar and having in its nozzle end a passage open to the atmosphere, an ink-suspension rod or governor, as D, independent of the feed-bar, having its forward end adapted to be passed through said open passage and suspended intermediate of the walls thereof to form an annular ink-weir, as b' , substantially as described.

17. A fountain-pen provided with a channeled feed-bar and with a passage in its nozzle end open to the atmosphere for the longitudinal adjustment of a governing-rod suspended therein independent of said feed-bar, said rod being adapted to form a rearwardly-flaring annular ink-weir, as b' , forward of the heel of the pen, which may be increased or decreased to regulate the flow of ink by longitudinal adjustment, substantially as shown and described.

18. In a fountain-pen wherein ink is fed by means of a feed-bar bearing upon the nibs of a pen as a safeguard against air forcing ink back out of feeding power to the pen, a non-elastic nozzle having a plurality of passages communicating rearward independently with the feed-supply and forward with one common passage near the heel of the pen, said plurality of passages being secured by the combination of the nozzle-case and a suitably-formed piece inserted therein, substantially as described.

19. A fountain-pen comprising in its construction an inclosed ink-channel disposed upon one side of the pen, as b^3 , and an annular ink-weir, as b' , adjacent to the pen on the opposite side.

20. A fountain-pen comprising in its organization and construction an eccentrically-disposed ink-passage in its nozzle, and a feed-bar shouldered as at e' , substantially as and for the purposes set forth.

21. A fountain-pen comprising in its construction an adjustable conduit having an ink-passage eccentrically disposed and a feed-bar shouldered as at e' , substantially as and for the purposes set forth.

22. A fountain-pen comprising in its organization and construction an angular repulsion-chamber, as a^2 , secured by adjusting the feed-bar shoulder e' inward beyond a right-angled shoulder, as b , formed in the mouth of the nozzle, substantially as and for the purposes set forth.

23. A fountain-pen provided with a nozzle having an ink-feeding channel on one side of the pen and a rod disconnected from the feed-bar and having its rear portion extending a suitable distance into the feed-supply and with its forward portion suspended intermediate of the walls of said nozzle to form an annular passage or chamber, as b^3 , communicating at its forward end with said ink-feeding channel and with a passage open to

the atmosphere upon one side of the pen only within the mouth of the nozzle, substantially as described.

24. In a fountain-pen, a nozzle having upon its periphery at the forward end an abrupt re-enforcement or ridge for a finger-stop to prevent the fingers sliding forward onto the pen, substantially as described.

25. A fountain-pen provided with a nozzle, as B, having an auxiliary frictional molding, as a' , separated from the cap-seat a^4 by a radial groove or depression a^8 , substantially as described.

26. A pen-shielding cap for fountain-pens provided with an index cross-bar H, substantially as and for the purposes described. 15

27. In a fountain-pen, in combination, the reservoir A, nozzle B, conduit B', feed-bar C, governor D, and pen C², all constructed to operate substantially as shown and described. 20

In testimony whereof I hereunto affix my signature in presence of two witnesses.

LAFOREST A. SHATTUCK.
